MATERIAL CUTTING DEVICE

Homer R. Rosenberry, Scudder, Ontario, Canada

Application May 9, 1949, Serial No. 92,163

4 Claims. (Cl. 30—15.5)

1

This invention relates to sheet-metal cutting and perforating in general, and relates particularly to an improved device for opening common metal food cans.

Sheet-material cutters and can openers can be fairly well classified into three types:

(1) A cutter wheel and a drive wheel mounted on a rotatable shaft, with a pressure-bearing member to serve as a cutting anvil. The cutting wheel is round with a smooth sharp cutting edge, and is forced along, much as the front wheel of a tractor is forced along, by the drive wheel. The drive wheel is usually knurled to bite into the surface of the metal for driving traction.

(2) The knife wheel and drive wheel are positioned on opposing movable members, thereby eliminating a separate pressure-bearing member.

(3) A fixed knife and a separate drive. The drive consists of a knurled drive wheel with means to force the drive wheel into driving engagement with the material to be cut.

The primary, but not the only weakness, with each of these devices is that the knurled drive wheel has a tendency to act as a milling cutter and cut into the soft material at the least resistance of the cutter tool to feed along the material.

An object of this invention is to provide a material-cutting device having one wheel with a cutting edge adapted to both drive the device and cut the material.

Another object of this invention is to provide a material-cutting wheel that cannot rotate with respect to the material, after engagement therewith, without cutting the material.

Another object of this invention is to provide an improved cutter adapted to pierce and then shear a series of small portions in linear alignment.

Another object of this invention is to provide a cutter adapted to pierce the material along the line of shearing just in advance of the actual shearing, to thereby interlock with the material and provide positive drive advancement of the cutter, but not producing any visible damage to the material other than the intended shearing after the cutter has passed.

Still another object of this invention is to provide a unique method of cutting and feeding with one tool in which a fixed track is utilized for locking the material to be cut by means of a plier action, said track acting as a guide.

A still further object of this invention is to provide a can opener device to indent a retainer ledge into the side of the can as the opener oper-

2

ates, and thereby prevent the severed lid from dropping into the can.

Other objects and a fuller understanding of the invention may be had by referring to the following description and claims, taken in conjunction with the accompanying drawings, in which:

Figure 1 is a top plan view of a material-cutting device incorporating features of my invention, and particularly adapted to open metal food cans;

10 Figure 2 is a side view of the device of Figure 1;

Figure 3 is a bottom view of the device of Figure 1;

Figure 4 is a bottom view of the device of Figure 1, with the handles opened to receive the material to be cut;

15 Figure 5 is a section taken along line 5—5 of Figure 1, with a portion of a metal food can added to illustrate the relative operative position of the can and opener;

20 Figure 6 is a perspective view of the improved cutter wheel;

Figure 7 is a section through the cutter wheel; and

25 Figure 8 is an enlarged illustration of several cutting teeth to show the series of teeth each in an advanced relationship of piercing and shearing action with respect to the tooth following.

In the drawing, a form of the preferred embodiment of this invention has been adapted for use in removing the tops from metal food cans. The illustrated can opener comprises a first handle 10 and a second handle 11 pivotally joined at one end thereof by means of a pivot 12.

The improved cutting device of this invention is rotatably carried on this handle 10 by means of a drive shaft 14 pivotally bearinged on the handle 10 and extending therethrough to drivingly support the wheel 13. In the illustrated embodiment, the drive shaft 14 is provided with a wing crank 15 for convenient finger gripping.

35 The second handle 11 is provided with a pressure-bearing track 19 in position to coact with said wheel 13 and press material into cutting relationship with the wheel 13 by pivotal closing of the first and second handles 10 and 11 together. In other words, material may be clamped by the pressure-bearing track 19 and the edge of the wheel 13 by closing the handles 10 and 11 toward one another.

40 Figures 6 and 7 illustrate the improved cutting device of this invention in the form of a wheel. The wheel 13 may be machined from a solid piece of material, but the illustrated embodiment is a stamping and is found to give very satisfactory service. It is preferable that the

wheel 13 be made of a material which may be conveniently hardened in order that longer service may be obtained before the wheel 13 wears out, but a soft steel cutting wheel has been made and used without heat treatment, and because of the superior cutting action provided did not wear out as quickly as the usual round cutting wheel normally employed in can-opening devices.

The wheel 13 is tapered at the peripheral edge thereof to an acute angle cutting edge 21, but the superior cutting action which I have discovered is provided by the tooth form and cutting action best illustrated in Figure 8.

The edge 21 of the wheel 13 is serrated to provide a series of cutting members 16 for piercing action followed by cleaving action over a short length of the material to be cut. The piercing and cleaving action is repeated in linear sequence until the desired severance has been accomplished. Furthermore, the improved serrated edge which is illustrated provides a positive driving action for the wheel in such a manner that the cutting wheel cannot rotate with respect to the material to be cut after engagement with the material. That is, the form of the cutting wheel both drives the cutting wheel and performs the cutting action, and absolutely prevents the cutting wheel from milling out a small portion of the material and thereafter simply turning in a fixed position with respect to the material without producing further cutting action.

This improved combination drive-piercing-cleaving action may be explained best with reference to the Figure 8. In the Figure 8 cutting members 16 on a small portion of the edge 21 are illustrated greatly enlarged. Each cutting member 16 is illustrated in the progressive positions of cutting to illustrate the individual tooth action as the wheel 13 progresses along the surface of the material to be cut. The edge 21, as before stated, is serrated, and thereby provides a plurality of cutting members 16 each having a piercing end 17 and a cleaving edge 18. In the Figure 8, the edge 21 of the wheel 13 has been forced into contact with the material to be cut until the ends 17 of cutting members 16 have pierced the material. The forcing may be done by means of the pressure-bearing track 19, as illustrated in the Figures 1 to 4, or by any other suitable means adapted to press the material against the wheel or to press the wheel against the material. The important consideration is that the wheel be pressed against the surface of the material to be cut with sufficient force to pierce the material and hold that force of the material and wheel so long as cutting action is desired. In Figure 8, it will be seen that cutting members 16 have been forced through the material to be cut with a piercing action. Thereafter the wheel 13 is rotated until each cutting member 16 rolls to the position of the next preceding tooth. It will be noted that the edges 18 of some cutting members 16 are just beginning to cleave the material to be cut, and that the piercing ends 17 of advanced cutting members 16 are approaching the metal to begin to pierce the material. The ends 17 of members 16 are therefore interlocked with the material when they pierce the material, and will force the wheel 13 to advance with respect to the material, and therefore force the cleaving edge 18 of following cutting members 16 to roll and cleave the material.

The angular edge 21 of the wheel 13, as the members 16 sever the metal, forces the severed

metal of the can back into tight contact with the side wall of the can substantially at the point indicated by the reference character 26 in Figure 5. The metal which is thus pressed tightly against the wall will be completely free of dangerous cutting points. However, a further feature than safety is obtained by folding the severed metal against the side wall, namely, that the folded metal stands out in relief from the can wall, and the sloping side 27 of the angular edge 21 will follow the folded material on a track. Thus, in addition to the piercing interlock of the members 16, the severed material folds back and acts as a drive track to provide positive drive of the cutting wheel 13.

Because each cutting member 16 performs the exact function as the preceding one, the Figure 8 actually may be thought of as a stroboscopic view of one or more cutting members 16. The Figure 8 clearly shows that the cutting members 16 act as interlocking drive members from the moment when they first pierce the material, and that from the moment of first piercing, each tooth cleaves by a combination punching and rolling action. After each cutting member first pierces the material, the cleaving by side 18 takes place in the direction of movement. Therefore, each member 16 enters the material and cuts forwardly until it cuts into the opening started by the tooth preceding.

The illustrated can opener embodiment of the invention has a further feature heretofore unknown to the industry. The track member 19 has for one function guiding and pressing the wheel 13 and the material together into cutting relationship. It has been found that the track members, as they move relative to the can wall, press a small indentation 25 into the can, thereby producing a throat of smaller dimension than the original can dimension. Therefore, when the lid is severed, it cannot fall into the can.

Another use to which this invention may be placed, as an illustration of its advantages, is the perforation of material to provide a line along which easy bending or tearing may be performed. To perforate without shearing, the cutting members 16 are spaced to prevent the above described joining of sequential severances. Thereby, a series of spaced incisions is provided by the piercing-followed-by-cleaving action, but the material is not severed.

The improved cutting action of this invention may be applied in many ways, and the illustrated embodiment is only for the purpose of setting forth one example. The method of drive, the method of providing piercing pressure and anvil backing, and the wheel form of the cutter may be varied to suit a particular adaptation without departing from the spirit and scope of the invention as hereinafter claimed.

What is claimed is:

1. Material-cutting device comprising, a driving and cutting wheel combination, said wheel having a center of rotation, a bottom wall of large diameter and a top wall of smaller diameter with a sloping edge wall therebetween, a continuous series of cutting members cut into said edge wall, each said cutting member having a substantially straight edge extending in a radial direction from said center, and a cleavage edge having a center of generation located away from the said center of the wheel, said straight edge and cleavage edge meeting at a piercing end point defining an included angle less than 90°, said cleavage edge of one cutting member meet-

ing the radially extending edge of an adjacent member and defining an included angle therewith not greater than 45°, means to rotatably drive said wheel, pressure-bearing jaw means, and means to force said pressure-bearing means toward said wheel, said pressure-bearing jaw means and said wheel acting as a clamp to hold a substance to be cut therebetween in a longitudinally slideable grip, but held against later movement away from said cutting wheel.

2. Material-cutting device comprising, first handle means and second handle means, pivot means joining said first and second handle means in lateral pivotable relationship, a driving and cutting wheel combination, means rotatably mounting said wheel on said first handle means with the wheel extending laterally in the direction of pivotal movement of said first handle, said wheel having a center of rotation, a bottom wall of large diameter and a top wall of smaller diameter with a sloping edge wall therebetween, a continuous series of cutting members cut into said edge wall, each said cutting member having a substantially straight edge extending in a radial direction from said center of rotation, a cleavage edge, said straight edge and cleavage edge meeting at a piercing end point defining an included angle less than 90°, said cleavage edge of one cutting member meeting the straight edge of an adjacent member and defining an included angle therewith not greater than 45°, means to rotatably drive said wheel, and pressure-bearing means mounted on said second handle means in position to coact with said wheel and press material into cutting relationship with said wheel by pivotally closing said first and second handle means together, whereby driving rotation of said wheel will cause said cutting members in sequential order to each pierce the material to be cut and roll with respect to the material and thereby cleave a series of continuous portions of said material and advance the material-cutting device with respect to the material.

3. Material-cutting device comprising, first handle means and second handle means, pivot means joining said first and second handle means in lateral pivotable relationship, a driving and cutting wheel, means rotatably mounting said wheel on said first handle means with said edge extending laterally in the direction of pivotal movement of said first handle, said wheel having a center of rotation, a first side wall of large diameter and a second side wall of smaller diameter with a sloping edge wall therebetween, a continuous series of cutting members cut into said edge wall to define a peripheral edge of the wheel, each said cutting member having a substantially straight edge extending in a radial direction from said center of rotation, and a cleavage edge formed by the junction of said edge wall and said first side wall, said straight edge

and cleavage edge meeting at a piercing end point defining an included angle less than 90°, said cleavage edge of one cutting member meeting the straight edge of an adjacent member and defining an included angle therewith not greater than 45°, means to rotatably drive said wheel, and pressure-bearing means mounted on said second handle means in position to coact with said wheel and press material into cutting relationship with said wheel by pivotally closing said first and second handle means together, whereby driving rotation of said wheel will cause said cutting members in sequential order to each pierce the material to be cut and roll with respect to the material and thereby cleave a series of contiguous portions of said material and advance the material-cutting device with respect to the material.

4. Material-cutting device comprising, first handle means and second handle means, pivot means joining said first and second handle means in lateral pivotable relationship, a driving and cutting wheel combination, means rotatably mounting said wheel on said first handle means with the wheel extending laterally in the direction of pivotal movement of said first handle, said wheel having a center of rotation, a bottom wall of large diameter and a top wall of smaller diameter with a sloping edge wall therebetween, a continuous series of cutting members cut into said edge wall, each said cutting member having a substantially straight edge extending in a radial direction from said center of rotation, a cleavage edge, said straight edge and cleavage edge meeting at a piercing end point defining an included angle less than 90°, said cleavage edge of one cutting member meeting the straight edge of an adjacent member and defining an included angle therewith not greater than 45°, means to rotatably drive said wheel, and pressure-bearing means mounted on said second handle means in position to coact with said wheel and press material into cutting relationship with said wheel by pivotally closing said first and second handle means together, said pressure-bearing means having an indentation-forming portion located at an elevation below said cutter wheel adapted to indent the material being cut below the cutting position.
